UNITED STATES PATENT OFFICE.

DAVID G. DEE, OF ROCHESTER, NEW YORK, ASSIGNOR TO DENIO GENERAL ELECTRIC COMPANY, OF ROCHESTER, NEW YORK, A CORPORATION OF NEW YORK.

FIRE-ALARM SYSTEM.

1,015,789.

Specification of Letters Patent.

Patented Jan. 30, 1912.

Application filed April 20, 1911. Serial No. 622,332.

To all whom it may concern:

Be it known that I, DAVID G. DEE, of Rochester, in the county of Monroe and State of New York, have invented certain new and useful Improvements in Fire-Alarm Systems; and I do hereby declare the following to be a full, clear, and exact description of the same, reference being had to the accompanying drawings, forming a part of this specification, and to the reference-numerals marked thereon.

The present invention relates to fire alarm systems, and it has for its object the provision of a fire alarm system operable 15 either manually or automatically and especially adapted for use in connection with telephone circuits, the arrangement being such that the operating mechanism for the fire alarm is controlled by a circuit which 20 is always closed.

18 is always closed.

25 A further object of my invention is to provide means for giving a signal to the central exchange from a subscriber's circuit whenever there is a break, ground, accidental short circuit, or other trouble in the fire alarm circuit, without operating the fire alarm itself, but permitting the fire alarm to be actuated, in case of fire, during the existence of the trouble condition in the 30 circuit.

To these and other ends the invention consists in certain improvements and combinations of parts all as will be hereinabove more fully described, the novel features being pointed out in the claims at the end of the specification.

The drawing is a diagrammatic view, illustrating one embodiment of the invention, as applied to two floors of a building, one floor employing a three wire fire alarm circuit with thermostatic and manually controlled circuit closers, and the other floor employing a two wire fire alarm circuit with manually controlled circuit closers.

45 The invention may be carried out in various ways, and a convenient application of it is disclosed in the present embodiment which involves a closed fire alarm circuit including a resistance element, the shunting of which by operation of the manually controlled or thermostatic circuit closers, serves 50 to effect operation of the fire alarm which is transmitted to the central exchange, and a break, ground, accidental short circuit or 55 other trouble in the fire alarm circuit serv-

ing to actuate a signaling device in the subscriber's circuit which, also, is transmitted to the central exchange, means being provided for simultaneously giving a local indication of the trouble in the fire alarm circuit, and for convenience in the following description the last mentioned signals will hereinafter be referred to as the central trouble signal, and the local trouble signal, respectively. 60 65

In the drawing A indicates the main telephone circuit, leading from the central exchange to the fire alarm box E, and C is the subscriber's circuit, connected with the main circuit A as usual. 70

D² and D⁸ are the fire alarm circuits, both connected through battery B to the alarm box E, as shown, the one comprising a two wire system including manually operated circuit closers, and the latter comprising a 75 three wire system arranged for either thermostatic or manually controlled circuit closers, the principle of operation being substantially the same for both.

The actuating mechanism for the alarm box E may be of any convenient form, and is controlled by a relay R, which is normally deenergized, and arranged to be energized upon the shunting of resistance in the fire alarm circuit. To this end, the circuit D³, in the present embodiment, includes relays R² and R³, and circuit D² includes relay R⁴. The relays R², R³ and R⁴ are normally energized by the current flowing through the fire alarm circuit from battery B, they being of approximately 200 ohms resistance

being of approximately 200 ohms resistance each to conveniently effect the desired purpose, and proportioned so that their armatures, when once released by the shunting of the current, are not again attracted by re-energizing the magnets but must be manually reset. The relays of the present embodiment include multiple point armatures, for a purpose which will presently be made clear, the armature of relay R^2 including contacts a, b, c, d , the armature of relay R^3 including contacts e, f, g , and the armature of relay R^4 including contacts h, i, j, k , contacts a, g and h being connected to the circuit F leading to the subscriber's circuit C and including therewithin the central trouble signal, comprising in the present embodiment, the relay R^5 , connected, as shown, and the armature of which is arranged to be vibrated upon the closing of

the circuit F by the alternate energizing and de-energizing of the electromagnet. Thus, when a break occurs within the fire alarm circuit, one of the controlling relays 5 releases its respective armature, according to the location of the break, to close circuit F and actuate the signal relay R⁵, which, by its operation, transmits a buzzing sound to the central operator, who is thus advised 10 that there is trouble somewhere in the fire alarm circuit. This action does not prevent the subsequent operation of the fire alarm box, in case of fire, but the latter is not operated to give an alarm as long as the resistance of a relay is included in the circuit. That is to say, the alarm is actuated from 15 circuit D² only when both relays R² and R³ are shunted and similarly from circuit D² when relay R⁴ is shunted. But the release 20 of any one of the armatures of the controlling relays will give a trouble signal to the central exchange.

In the normal operation of the fire alarm circuit D³, the current passes from battery 25 B to relay R⁵, to relay R², to annunciator H², to relay R⁷, to relay R of the alarm box, and back to the battery. For circuit D² the current normally passes from battery B to relay R⁴, to annunciator H², to relay R⁷, to 30 relay R of the alarm box, and back to the battery. In case of a break, or accidental short circuit in the circuit D³, one of the relays R², R³ will be shunted, releasing its 35 armature and closing the trouble signal circuit, but the other relay will still be in the circuit, presenting sufficient resistance to prevent the operation of the alarm box controlling relay R. In the event of a fire, causing operation of the thermostatic circuit 40 closers, or necessitating the operation of the manually controlled circuit closer, both relays R² and R³ are shunted, and the relay R of the alarm box is energized to attract its armature and effect operation of the alarm, 45 which is transmitted to the central exchange. In case of a break or other trouble in circuit D², the armature of relay R⁴ is released, but provision is made by means of contact k and its connections, for causing 50 the current to pass through the electromagnet R⁴ by a different path, thus continuing the resistance in the circuit and preventing operation of the alarm, but giving the trouble signal to the central exchange by the 55 closing of the trouble signal circuit through contact h. If one of the manually controlled circuit closers of circuit D² is closed, the relay R⁴ is shunted, causing the relay R at the alarm box to be energized and the 60 alarm to be sent in to the central exchange.

In the event of trouble in the fire alarm circuit, and transmission of the trouble alarm to the central exchange, it is desirable also to give to the subscriber an indication of the trouble in the alarm circuit,

and to this end, I provide a local trouble signal, which in the present embodiment includes a bell G connected to battery B², the local trouble circuit being suitably connected to contacts b, f and i of the relays R², R³ and R⁴, respectively, so that in the event of closure of the main trouble signal circuit by any one of the controlling relays, the local trouble signal circuit is also closed and indication thereby given to the subscriber that a break or other trouble exists somewhere in the circuit. It is further desirable to give a trouble signal to the central exchange and to the subscriber in case of a ground in the alarm circuit, and to this end a convenient means, illustrated in the present embodiment, consists in splitting the battery B and making connection therefrom to the ground through the two point relay R⁶. The contacts l and m of relay R⁶ are 85 connected, respectively, with the main trouble signal circuit F and with the local trouble signal circuit including the bell G, so that in case of a ground in the alarm circuit, the relay R⁶ is energized, attracting its armature and closing the trouble signal circuits, thus giving an indication to the central exchange and to the subscriber that there is a ground in the alarm circuit.

In order to indicate to the subscriber the particular location of the fire in the building, in case of the operation of the fire alarm, there are provided the annunciators H² and H³ arranged, respectively, in the alarm circuits D² and D³, so as to be actuated upon the shunting of the resistance in the respective circuit.

To the end that signals may be given in the different parts of a building in which the fire occurs, there are provided suitable alarms K² and K³ connected in a circuit with the battery B³, which circuit is arranged to be closed upon the attraction of the armature of relay R¹ adapted to be energized when the fire alarm is given to the central exchange, upon the shunting of the resistance in the fire alarm circuit.

The subscriber's circuit is automatically cut out of the main telephone circuit upon operation of the fire alarm by the release of the spring-controlled switch arm m, which is held normally in engagement with the contact n by the projection o, carried by the fire alarm wheel p. As soon as relay R is energized, the alarm wheel p commences to rotate, being released by armature q, and moving the projection o out of engagement with the switch arm, which falls away and breaks circuit C, the main circuit A being kept closed by a suitable connection between the switch arm m and the alarm wheel p.

I claim as my invention:

1. The combination with a main telephone circuit and a subscriber's circuit, of a closed fire alarm circuit adapted to control the sub-

- scriber's circuit, a resistance element included in the fire alarm circuit, an alarm associated with the fire alarm circuit and with the main telephone circuit, and means controlled by shunting the resistance element in the fire alarm circuit for operating the alarm. 5
2. The combination with a main telephone circuit and a subscriber's circuit, of a signal included in the subscriber's telephone circuit, a closed fire alarm circuit adapted to control the subscriber's circuit, resistance elements included in the fire alarm circuit, an alarm associated with the fire alarm circuit and with the main telephone circuit, and means controlled by shunting one of the resistance elements in the fire alarm circuit for operating the signal in the subscriber's circuit. 10
- 20 3. The combination with a main telephone circuit and a subscriber's circuit, of a signal included in the subscriber's circuit, a closed fire alarm circuit adapted to control the subscriber's circuit, an alarm associated with the fire alarm circuit and with the main telephone circuit, a resistance element included in the fire alarm circuit, means controlled by a break or ground in the fire alarm circuit for operating the signal in the subscriber's circuit, and means controlled by shunting the resistance in the fire alarm circuit for operating the alarm. 15
4. The combination with a main telephone circuit and a subscriber's circuit, of a signal included in the subscriber's telephone circuit, a closed fire alarm circuit adapted to control the subscriber's circuit, a plurality of resistance elements included in the fire alarm circuit, an alarm associated with the fire alarm circuit and with the main telephone circuit, means controlled by shunting one of the resistance elements in the fire alarm circuit for operating the signal in the subscriber's circuit, and means controlled by shunting all of the resistance elements in the fire alarm circuit for operating the alarm. 20
5. The combination with a main telephone circuit and a subscriber's circuit, of a signal included in the subscriber's telephone circuit, a closed fire alarm circuit adapted to control the subscriber's circuit, an alarm associated with the fire alarm circuit and with the main telephone circuit, a resistance element included in the fire alarm circuit, means controlled by a disturbance in the fire alarm circuit for operating the signal in the subscriber's circuit, and means controlled by the shunting of the resistance in the fire alarm circuit for operating the fire alarm. 25
6. The combination with a main telephone circuit and a subscriber's circuit, of a signal included in the subscriber's circuit, a closed fire alarm circuit adapted to control the subscriber's circuit, an alarm associated with the fire alarm circuit and with the main telephone circuit, means controlled by a break or ground in the fire alarm circuit for operating the signal in the subscriber's circuit, means controlled by short circuiting the fire alarm circuit for operating the alarm. 30
7. The combination with a main telephone circuit and a subscriber's circuit, of a signaling relay included in the subscriber's circuit, a closed fire alarm circuit adapted to control the subscriber's circuit, a relay included in the fire alarm circuit, a fire alarm associated with the fire alarm circuit and with the main telephone circuit, means controlled by the armature of the fire alarm circuit relay for operating the signaling relay in the subscriber's circuit, and means controlled by the shunting of the fire alarm circuit relay for operating the alarm. 35
8. The combination with a main telephone circuit, and a subscriber's circuit, of a signaling relay included in the subscriber's circuit, a closed fire alarm circuit adapted to control the subscriber's circuit, a pair of relays included in the fire alarm circuit, a fire alarm associated with the fire alarm circuit and with the main telephone circuit, means controlled by the shunting of one of the fire alarm circuit relays for operating the signaling relay in the subscriber's circuit, and means controlled by the shunting of both the fire alarm circuit relays for operating the alarm. 40
9. The combination with a main telephone circuit and a subscriber's circuit, of a signal included in the subscriber's telephone circuit, a closed fire alarm circuit adapted to control the subscriber's circuit, resistance elements included in the fire alarm circuit, an alarm associated with the fire alarm circuit and with the main telephone circuit, means controlled by shunting one of the resistance elements in the fire alarm circuit for operating the signal in the subscriber's circuit, and a local trouble signal arranged to be actuated upon the operation of the signal in the subscriber's circuit. 45
10. The combination with a main telephone circuit, and a subscriber's circuit, of a signal included in the subscriber's circuit, a closed fire alarm circuit adapted to control the subscriber's circuit, an alarm associated with the fire alarm circuit and with the main telephone circuit, a resistance element included in the fire alarm circuit, means controlled by a break or ground in the fire alarm circuit for operating the signal in the subscriber's circuit, means controlled by shunting the resistance in the fire alarm circuit for operating the alarm, and a local trouble signal arranged to be actuated upon the operation of the signal in the subscriber's circuit. 50
11. The combination with a main telephone circuit, and a subscriber's circuit, of a signal included in the subscriber's telephone circuit, means controlled by a break or ground in the fire alarm circuit for operating the signal in the subscriber's circuit, and means controlled by short circuiting the fire alarm circuit for operating the alarm. 55

- 4
1. circuit, a closed fire alarm circuit adapted to control the subscriber's circuit, a plurality of resistance elements included in the fire alarm circuit, an alarm associated with the fire alarm circuit and with the main telephone circuit, means controlled by shunting one of the resistance elements in the fire alarm circuit for operating the signal in the subscriber's circuit, means controlled by shunting all of the resistance elements in the fire alarm circuit for operating the alarm, and a local trouble signal arranged to be actuated upon the operation of the signal in the subscriber's circuit.
2. The combination with a main telephone circuit and a subscriber's circuit, of a closed fire alarm circuit adapted to control the subscriber's circuit, an alarm associated with the fire alarm circuit and with the main telephone circuit, a resistance element included in the fire alarm circuit, means controlled by a disturbance in the fire alarm circuit for operating the signal in the subscriber's circuit, means controlled by the shunting of the resistance in the fire alarm circuit for operating the fire alarm, and a local trouble signal arranged to be actuated upon the operation of the signal in the subscriber's circuit.*
3. The combination with a main telephone circuit and a subscriber's circuit, of a signal included in the subscriber's circuit, a closed fire alarm circuit adapted to control the subscriber's circuit, an alarm associated with the fire alarm circuit and with the main telephone circuit, means controlled by a break or ground in the fire alarm circuit for operating the signal in the subscriber's circuit, means controlled by short circuiting the fire alarm circuit for operating the

alarm, and a local trouble signal arranged to be actuated upon the operation of the signal in the subscriber's circuit.

4. The combination with a main telephone circuit, and a subscriber's circuit, of a signaling relay included in the subscriber's circuit, a closed fire alarm circuit adapted to control the subscriber's circuit, a relay included in the fire alarm circuit, a fire alarm associated with the fire alarm circuit and with the main telephone circuit, means controlled by the armature of the fire alarm circuit relay for operating the signaling relay in the subscriber's circuit, means controlled by the shunting of the fire alarm circuit relay for operating the alarm, and a local trouble signal arranged to be actuated upon the operation of the signaling relay in the subscriber's circuit.

5. The combination with a main telephone circuit, and a subscriber's circuit, of a signaling relay included in the subscriber's circuit, a closed fire alarm circuit adapted to control the subscriber's circuit, a pair of relays included in the fire alarm circuit, a fire alarm associated with the fire alarm circuit and with the main telephone circuit, means controlled by the shunting of one of the fire alarm circuit relays for operating the signaling relay in the subscriber's circuit, means controlled by the shunting of both the fire alarm circuit relays for operating the fire alarm, and a local trouble signal arranged to be actuated upon the operation of the signaling relay in the subscriber's circuit.
